HENRIK J. SCHMIDT, OF BROOKLYN, NEW YORK, ASSIGNOR TO C. FREDERICK RAICHLEN, OF BAYONNE, NEW JERSEY.

MACHINE FOR TYING PACKAGES.

1,392,972.

Specification of Letters Patent. Patented Oct. 11, 1921.

Application filed August 7, 1920. Serial No. 401,986.

To all whom it may concern:

Be it known that I, HENRIK J. SCHMIDT, a subject of the King of Denmark, residing at Brooklyn, in the county of Kings and 5 State of New York, have invented certain new and useful Improvements in Machines for Tying Packages, of which the following is a specification.

My invention relates to a machine for 10 tying packages and to an improved method, and although various features thereof are applicable to other uses, yet the machine and method are particularly adapted for tying ribbons or cords in a bow-knot 15 around packages, such as packages of envelopes, or around candy boxes, toilet articles and the like.

The main and particular objects of the invention are to produce a method and a 20 machine whereby a minimum amount of operation is required, a high degree of accuracy in operation is attained, a high degree of speed, and a minimum amount of manipulation is required by the attendant 25 of the machine. The only duty required of the operator in the preferred embodiment of my invention is to insert and remove the packages, the machine completing the wrapping and tying of the ribbon, or cord, in a 30 bow-knot. Another object is to devise a machine which will accomplish the above purpose and adapt the same to be driven from a source of power, such as an electric motor or other source. Another object 35 is to so inter-relate the parts and their sequence of movement that the number of parts and their functions will be reduced to a minimum of simplicity and attain a high degree of durability and thus insure 40 long continued operation without the necessity of material interruptions or stoppage of the machine for repairs or adjustments. Another object is to provide a machine in which the packages, or object to be 45 wrapped, can be quickly and conveniently fed to and removed from the machine.

These and various other objects and advantages of the machine and method will be understood from the following description 50 and accompanying drawings which illustrate a preferred embodiment of my invention, although various modifications thereof may be made without departing from the scope of the invention.

Figure 1 is a front elevation of a preferred embodiment of my invention;

Fig. 2 is a cross-section on the line 2—2 of Fig. 1;

Fig. 3 is a plan view of the lower portion of the machine with certain parts broken away.

Fig. 4 is a development of three cams of the lower portion of the machine showing their relative positions;

Fig. 5 is a plan view showing certain parts in their relative positions after the first knot has been formed;

Fig. 6 is a plan view of the upper portion of the machine;

Fig. 7 is a development of four cams on the shaft of the upper portion of the machine showing the relationship of the cams;

Fig. 8 is a side elevation of certain parts of the ribbon or cord drawing mechanism;

Fig. 9 is a side elevation with parts in section of a portion of the ribbon or cord cutting mechanism;

Fig. 10 is a plan view of certain parts showing their relationship in the process of forming the bow, and

Fig. 11 is a similar view of the parts after the bow has been formed, but before the parts have been drawn from the bow.

In a general way the machine illustrated herewith comprises a main base portion 85 which receives the packages and which functions to draw the ribbon under the package and cut the same to a proper length. It also functions to wrap the ribbon around the package and to form the first knot and to 90 place the long ends of the ribbon in position to be received and manipulated by the upper portion of the machine which forms and ties the bow. The upper portion of the machine is here shown as having the general form 95 of a bridge which is kept elevated until the lower portion of the machine has completed wrapping and tying of the first knot and is then lowered and functions to tie the bow, after which it is raised until the lower portion 100 of the machine has wrapped and tied the next package, at which time the upper portion of the machine again comes into play to form the bow on the second package and so on. All of the parts are driven from a single source of power, the act of lowering the upper portion of the machine causing it to be automatically connected up and driven

80

100

105

from the same source which operates the lower portion of the machine, the raising of the upper portion automatically disconnecting itself from the source of power.

5 Referring first to the lower portion of the machine and particularly to Figs. 1, 2, 3 and 4, there is provided a main supporting shallow base portion 1 of rectangular form having four downwardly extending legs at the 10 corners and a plate portion 1^a, which latter forms the main support for the parts. Near the left-hand end of the plate 1^a is an upwardly extending pedestal or bearing 2 for a shaft carrying a pulley 3 driven by a 15 belt 4, which is the source of power for operating the mechanism, although any other suitable source or driving means may be used. The driving shaft carries a large gear 5 which extends downwardly through an 20 opening in the plate 1^a and drives a second gear 6. The latter gear is mounted upon shaft 7 which is journaled in pedestals 8 extending downwardly from the underside of plate 1^a. The shaft 7 has fixed thereto the 25 three cylindrical cams 9, 9^a, 9^b, the development of which and relative position on the shaft 7 being shown in Fig. 4. The gear 6 engages another gear 10 of the same size and number of teeth as gear 6, the gear 10 being 30 fixed to a shaft 11, which latter is journaled in the ends of the base 1. The shaft 11 carries plate cams 12, one at each end of the shaft, for raising and lowering the upper portion of the machine, as will be later described. The shaft 11 also carries a plate 35 cam 13 which actuates the cutting mechanism.

The spool 14 of ribbon 15 is mounted on any suitable support. The ribbon passes 40 through a slot 16 at the right-hand front corner of the base and extends along the length of the base through a slot 16'. The means for drawing the ribbon through the machine and under the package is operated 45 by the cam 9^a. A lever 17 is pivotally mounted at 17^a on a fixed support extending down from the underside of the plate 1^a. The front end of lever 17 carries a pin 17^b, which engages the groove 17^c of the cam 9^a. 50 The rear end of the lever 17 extends upwardly and has a slotted connection with the rear end of a lever 18 pivoted at 18^a on the underside of the plate 1^a. The lever 18 extends forwardly and has a downward bent 55 end and has coupled thereto a slidable extending portion 18^b. The part 18^b is secured to the underside of the front portion of the lever 18. The part 18^b carries a pin 18^c on its underside from which a spring 18^d extends to a pin 18^e, which latter is secured to the underside of the lever 18. The pin 18^e passes through a slot 18^f in the extension 18^b to permit free inward and outward movement of the extension 18^b. The outer end of 60 65 the lever 18 and the inner end of lever 18^b

carry clips 18^g fixed thereto which slidably engage the edge of the other lever respectively for guiding purposes and for keeping the parts in alinement. The spring 18^d thus tends to constantly draw the extension 70 18^b backwardly and tends always to shorten the length of the coupled parts.

The outer end of the lever portion 18^b carries a roller 18^h on its under side, which engages the front edge of a guide plate 20 75 fixed in a horizontal position and below the base plate 1^a by supporting studs 20^a. The front edge of this guide plate 20 has a contour as shown by dotted and full lines in Fig. 3 so that when the lever 18 is swung 80 from left to right, or the reverse, the outer end of the part 18^b will follow the contour of the front edge of plate 20, because the spring 18^d always holds the roller 18^h in contact with the edge of the plate 20 and permits inward and outward movement of the 85 outer end of lever 18^b as required by the shape of the plate 20.

On the upper side of the front end of the lever extension 18^b is fixed a post 21 having 90 a backwardly extending lip 21^a, which extends under the ribbon 15 as particularly shown in Fig. 8. On the post is pivoted a finger or plate 21^b, which is pressed by the spring 21^c to normally clamp the ribbon 15 95 between it and the lip 21^a. The post 21 is cut away at the upper front corner to permit the front end of the plate 21^b to move downwardly when it strikes a pin or projection 21^d on the under side of a cut-away 100 part of plate 1^a. A projection 21^d is located at each end of the stroke of the lever 18^b so that in each of these positions the ribbon 15 is not held by the ribbon drawing mechanism. 105

It will be seen that when the cam 9^a is turned by the shaft 7, it will cause the lever 17 to be turned about its pivot 17^a and cause the lever 18 and 18^b to be turned about their pivot 18^a; and the shape of the cam 9^a as 110 shown in Fig. 4 will cause, when starting from the upper part of the cam 9^a shown in Fig. 4, the lever 18 and 18^b to be thrown from a right-hand position to the position shown in Fig. 3. When in the right-hand 115 position, the plate or finger 21^b is raised and the end of the ribbon 15 is then located in the ribbon drawer as shown in Fig. 8. When the lever 18 moves from the right-hand position, it causes the finger 21^b to be released and it 120 then clamps the ribbon 15 against the lip or finger 21^a, and consequently draws the ribbon along the path of the outer end of lever 18^b to the position shown in Fig. 3. At this point the front end of the finger 21^b 125 is engaged by the other projection 21^d and the ribbon is then released. It will be seen that by the shape of the cam 9^a, the lever 18 remains in its left-hand position, as shown, for a considerable part of the revolution of 130

shaft 7, after which it is caused to take a reverse movement to the right and again grip the end of ribbon 15. It then immediately swings to the left where it again releases the ribbon and remains at the left during a fixed period and then it is again swung to the right, and so on. It should be noted that the base plate 1^a is thinned on its underside in a lengthwise direction along the path of the ribbon holding post to allow unobstructed movement of the same, as indicated in Figs. 2 and 8.

The mechanism for cutting the ribbon will now be described. The cam 13 which is fixed on shaft 11 is embraced on each side by a fork 13^a carried by each of two side pieces 13^b connected together and forming a supporting bracket fixed to the frame 1 at 13^c, as shown in Fig. 2. Between the side pieces 13^b is pivotally mounted a lever 13^d at the pivot 13^e and carries a roller 13^f at its rear end which engages the periphery of cam 13, the shape of which is shown in Fig. 9. The front end of lever 13^d carries a roller 13^g, which engages the upper edge of a lever 13^h, which has its front end pivoted at 13ⁱ between the side pieces 13^b and its rear end is slotted to engage a pin 13^j carried by the cutting plunger 13^k. A spring 13^l is secured at its lower end to the pivoted arm 13^h and at its upper end to the underside of the base plate 1^a and thus tends to draw the arm 13^h and plunger 13^k upwardly against the cam controlled lever 13^d. The cutting plunger 13^k has a diagonally formed upper cutting edge for cutting the ribbon. The cutting plunger is guided at its lower end by a part 13^m which is part of and connects the side pieces 13^b. The upper part of the cutting plunger is guided by a part 13ⁿ secured to the base plate 1^a. Above the cutting plunger is located a plate 13° secured to the top of the base plate 1^a and against which the cutting plunger is forced when cutting the ribbon 15.

It is evident that revolution of the cam 13 will cause the cutting plunger to be forced upwardly and to cut the ribbon once for each revolution of the cam, the periphery 50 of the cam having the cut away portion as shown in Fig. 9 into which the roller 13^f is about to drop, which permits the spring 13^l to throw the cutting plunger upwardly to cut the ribbon. The roller 13^f is then forced upwardly by the cam and the cutting plunger brought to its lower position, where it remains during the remaining portion of the revolution of the shaft 11. The cam 13 is so positioned on the shaft 11 that it causes 55 the cutting plunger to rise and cut the ribbon immediately after the ribbon drawing mechanism has reached the left-hand position shown in Fig. 3. It does not again come into action until after the ribbon drawing arm has been moved to the right and

again clamped and drawn the new end of the ribbon to the left-hand position, at which time the plunger cuts off the new length of ribbon.

I will now describe the mechanism and method for tying the first knot about the package. The frame 1^a is cut away in the front central portion as shown at 1^b sufficiently to allow the attendant to place the package to be wrapped in the position on 75 the base plate 1^a. A package of envelops A is here illustrated as an example, and the package is placed endwise against a back plate 1^c upwardly extending from the surface of the base plate 1^a. A plate 1^d is 80 adapted to rest over or on top of the package A when the package of envelops is inserted thereunder. It will be seen from Figs. 1, 2, and 3 that the package A when inserted in position to be wrapped, is positioned over the slot through which the ribbon 15 passes. The package A, when inserted, is also under two pivoted arms 22, 23, each of the outer ends of which are crossed over the other arm respectively. The arm 90 22 is pivoted at 22^a in a slidably movable pedestal 22^b. From this pedestal the arm 22 extends backwardly and upwardly over the package A and then downwardly at the right-hand end into a slot in the base plate 95 1^a. The lower end extends a short distance in a horizontal direction in the slot and has a forwardly extending end or finger 22^c at right angles thereto. The part 22^c when in this position extends under the ribbon 15 100 as shown in Fig. 3. Pivotally mounted on this right-hand end of arm 22 is a plate or finger 22^d having a similar right angle form to that of the end of the arm, but the forwardly extending part or finger of plate 22^d 105 is longer than the part 22^c. A leaf-spring 22^e is secured to the arm 22 near its right-hand end and presses against the plate or finger 22^d tending to hold it in engagement with the extension of the arm 22^c; but when 110 in the position shown in the drawings where the right-hand end of the arm 22 has been dropped into the slot in the base, the extended end of the finger 22^d engages the surface of the base plate 1^a and opens it from the finger 22^c against the pressure of the spring 22^e. This permits the ribbon to be passed between the parts 22^c and 22^d, but when the right-hand end of the arm 22 is raised, the finger 22^d is forced by its spring 115 120 against the part 22^c and the ribbon is thus clamped between these parts.

As stated before, the left-hand end of arm 22 is pivoted in the pedestal 22^b and passes through this pedestal and has fixed 125 to or formed at the front of its left-hand end, a dog 22^f, which is at an angle to the arm 22 and extends downwardly against the surface of the base plate 1^a, thus in effect forming a bell crank lever. It is thus evi- 130

dent that when the dog 22^f is turned in a counter-clockwise direction, the right-hand end of the arm 22 will be raised. It will be noted that the pedestal 22^b is located on the base plate in front of the slot containing the ribbon.

The arm 23 is similarly mounted and has parts corresponding to those already described and which are lettered respectively, 10 23^a to 23^f, but the pedestal 23^b which pivotally supports the arm 23 is located at the other side of the ribbon slot and beyond the arm 22. The arm 23 extends from the pedestal forwardly under arm 22 and upwardly 15 over the package A and downwardly over the left-hand portion of arm 22 and has the fingers 23^c and 23^d extending rearwardly and located below and above the ribbon respectively.

20 The pedestal 23^b is slidably mounted on the base plate and has a part 23^e extending down through the base and carrying a collar 23^h which holds the pedestal to the base. The part 23^e is slidable in the inclined slot 23ⁱ in the base. The pedestal 22^b has corresponding parts and is slidable along the line of the inclined slot 22ⁱ in the base. When pedestal 22^b is slid from the position shown in Fig. 3 to the left, the dog or pawl 22^f engages a raised strip 22^g which extends along the surface of the base plate parallel with the slot 22ⁱ. This turns the arm 22 about its pivot in a counter-clockwise direction and raises the free end of the arm a 35 considerable distance upwardly so that when the pedestal 22^b is moved to the left, the distant end of arm 22 will pass quite a little above the package A. Similarly the dog 23^f of the arm 23 engages a raised strip 23^g which extends along the top of the base plate parallel with the slot 23ⁱ; and when the pedestal 23^b is moved to the right from the position shown in Fig. 3, the distant end of the arm 23 is swung upwardly so that in the 40 movement of the pedestal 23^b to the right, the distant end of the arm 23 will pass over the package A some distance above it. One of the raised strips, 22^g, has a little greater height than the other strip, 23^g, for the purpose of causing the end of the arm 22 which carries the ribbon to be raised a little above the corresponding end of the arm 23 for passing by each other. Also the inclination of the slots 22ⁱ, 23ⁱ, causes the arms to pass 45 each other in forming the first knot and to give the ends of the ribbon certain positions. This particular action will be better understood from the description of operation to be later explained. It may be here stated, 50 however, that when the pedestal 23^b has reached the right-hand end of slot 23ⁱ, referring to Fig. 3, and when the pedestal 22^b has reached the left-hand end of slot 22ⁱ, the ribbon has been wrapped around the 55 package A and the first knot has been 60 65

formed, and the ends of the ribbon are held by the ends of the arms 22 and 23, as indicated in Fig. 5. From the knot the ribbon extends diagonally upward on each side and somewhat inclined, as shown in Fig. 5, to the holding ends of the arms 22, 23, the free ends of the ribbon hanging downwardly at the holding ends of these arms.

The means for causing the arms 22 and 23 to be moved from the position shown in Fig. 3 to that in Fig. 5 to form the first knot will now be described. Referring first to the pedestal 23^b, the part 23^g which extends through the base plate has a pin, which engages a slot in the front end of lever 24 forming a pivotal pin and slot connection therewith. The lever 24 is pivoted at 24^a to a stud fixed on the underside of the base plate, and its rear end has a pin and slot pivotal connection 24^b with the rear end of another lever 24^c. The latter lever is pivoted at 24^d on a support fixed to the underside of the base plate and its front end has a pin or roller 24^e, which engages the groove 24^f of the cam 9^b. The rear end of lever 24^c is bent to extend upwardly so as to make the pivotal connection with the rear end of lever 24. A lever 25 is similarly connected to pedestal 22^b and provided with corresponding parts as already described and correspondingly lettered 25 to 25^f. Supporting and guiding strips 19 and 19^a are secured to the underside of the base plate 1^a to serve as guides and supports for the levers in their movement.

In the position shown in Fig. 3, the ribbon drawing mechanism has caused the ribbon to be passed between the open fingers of the arms 22 and 23; and the cam shaft 7 has turned to the position so that the pins 24^e and 25^e are about to engage the first inclined portion of the cams 9 and 9^b. Further movement of the cams will evidently cause the front ends of arms 24^c and 25^c to be forced outwardly and the rear ends toward each other; this consequently causes the rear ends of levers 24 and 25 to be thrown toward each other about their pivots and causes the front ends of these levers to be separated and their pedestals to move to the outer ends of the slots 22ⁱ and 23ⁱ bringing these arms and ribbon to the position shown in Fig. 5 as already described.

The ribbon is next acted upon by the upper mechanism of the machine, which is now lowered. The upper mechanism is carried by a flat horizontal bar 26 forming a bridge which is slidably up and down. At the ends of the bar are heads 26^a which slidably engage vertical guides 26^b fixed to the lower frame 1. A downward projection 26^c extends from each end of the bar 26 and carries a roller 26^d. The two rollers engage respectively the periphery of cams 12, which as before stated are fixed to shaft 11. The

outline of cams 12 is shown in Fig. 2 and is such that, during the movements already described, the rollers 26^a are on the higher portion of the cams 12 so that the bridge is 5 raised, but at the completion of the movements above described, the cams 12 permit the rollers 26^a and the bridge to fall to its lower position, where it remains during the completion of the tying of the bow by the 10 bridge carrying mechanism.

The bar 26 has a pair of rearwardly extending journals 26^e for the cam shaft 27. The cam shaft 27 carries at the left hand end a pinion 27^a located immediately above the 15 driving gear 5 so that when the upper mechanism is lowered, the pinion 27^a will be engaged and driven by the gear 5. The pinion or gear 27^a is about one-half the size of gear 6, so that during about half a revolution 20 of the shaft 7, during which its cams cause no operation of their mechanism, the gear 27^a and shaft 27 will make a complete revolution. The shaft 27 carries cylindrical cams 28, 28^a, 28^b and 28^c, the development of 25 which is shown in Fig. 7 in their relative positions.

The hub of the gear 27^a, or a collar or sleeve 27^b fixed to the shaft 27, is recessed or indented at one point of its surface to receive a projection 27^c (see Fig. 2) carried at 30 the end of a leaf spring 27^d. This holds the shaft 27 always in the same angular position before and after a revolution of shaft 27, but its holding force is overcome by the driving 35 force of gear 5 when gear 27^a is driven thereby. This releasable holding device insures the proper teeth of gears 5 and 27^a being engaged each time the upper mechanism is lowered, and prevents over-running of shaft 40 27 after it has made one revolution.

Extending upwardly and forwardly from the support 26 are arms 26^e which carry in their front ends a horizontally slidable bar 29 carrying a few teeth at its central portion forming a rack. The arms 26^e have upwardly extending toward each other arms 26^f which support a vertical cylindrically shaped support 26^g. This support has fixed therein a downwardly extending shaft 29^a, 50 the lower end of which is reduced in size and carries a pin 29^b. A gear 29^c is carried by a sleeve 29^d rotatable and slidable on shaft 29^a and is pressed downwardly by the spiral spring 29^e encircling the vertical 55 shaft above the gear 29^c and pressing against the support 26^g at its upper end. The gear 29^c is engaged by the teeth of the rack 29. Fixed on the shaft 29^a below the sleeve 29^d is another sleeve 29^f. The upper end of this 60 sleeve and the lower end of sleeve 29^d are cut away as indicated in Figs. 1 and 2 to have cam surfaces, so that when the gear 29^c is rotated, it will also move downwardly from the position shown in accordance with 65 the contour of the opposed faces of these

sleeves. The movable sleeve 29^d also has secured thereto a leaf spring 29^g, at the lower end of which is a downwardly and outwardly extending rod 29^h carrying at its lower end a hook 29ⁱ. Fixed to sleeve 29^f is a disk or 70 cam 29^j against the periphery of which the rod constantly bears by pressure of the spring 29^g. The contour of disk 29^j is shown in Fig. 6 and is so shaped that the rod 29^h is swung in a counter-clockwise direction 75 looking at Fig. 6, the rod will be permitted to gradually swing toward its axis of rotation when the gear 29^c is rotated by the rack moving from right to left. Thus this movement of the rack causes the hook 29ⁱ to be 80 moved in a circular direction and at the same time downwardly and inwardly back of the shaft 29^a. The disk or cam 29^j is shaped to provide a stop at the rear and at the front to prevent the rod 29^h from being 85 swung beyond certain limits. The teeth of the rack 29 project beyond the front surface of the rack bar so that further movement of this bar to the left is permitted after the teeth have passed out of engagement 90 with the gear 29^c.

The movement of the rack 29 is controlled by the cam 28, through a connecting lever. A pin engages the groove or cam 28 at the rear end of arm 30 of the lever and is connected to the sleeve 30^a pivoted on a support 30^b extending upwardly from the plate 26. From the upper end of sleeve 30^a, a forwardly extending arm 30^c of the lever is pivotally connected by a pin and slot 100 connection, to the left hand end of the rack bar 29. A downwardly projecting stud 30^d extends from the plate 26 opposite the stud 30^b and a pin or shaft extends therethrough to which the sleeve 30^a of the lever is fixed 105 and at the lower end of which is fixed a sleeve 30^e, which carries a rearwardly extending arm 30^f. It is evident that rotation of the cam 28 will cause the lever 30 to be operated at the proper time to draw 110 the rack 29 to the left and so impart the movement above described to the hook 29ⁱ. It will be seen that by the shape of the cam 28 in Fig. 7, that after the rack has been drawn to the left so that it no longer engages the gear 29^c, a further movement or kick is given to control the movement of the arm 30^f for the purpose to be later described.

The cam 28^b controls another lever 31, 120 the arm 31 of which extends under the cam 28^b and has a pin engaging the same on its under side. This lever is pivoted in a boss 31^a extending downwardly from the front edge of the bar 26. The lever has an arm 31^b which extends in an inclined direction forwardly and downwardly. Pivoted on the front end of this arm 31^b and on its under side is another lever having an arm 31^c which projects from the under side of arm 31^b 130

somewhat to the right, and it also has an arm 31^a, which extends inwardly to the left and which carries a hook or pin 31^c. The arm 31^c has a projection 31^f which extends 5 slightly above the plane of the arm 31^b and the latter arm also has a similar upward projection 31^g. Between these little projections is located a spring 31^h, the ends of which are attached to these projections, and 10 the spring is under tension so that it constantly tends to draw the arm 31^c under the arm 31^b in the position shown in Fig. 6 and therefore it tends to hold the hook 31^c inwardly. The arm 31^c has a downwardly 15 turned end 31ⁱ.

The cam 28^e is engaged on its under side by a pin carried on the inner end of an arm 32 of a lever which is pivotally mounted on a boss 32^a extending downwardly from the 20 plate 26. The front arm of this lever is designated as 32^b and its front end when actuated by the cam is adapted to strike the projection 31ⁱ of the arm 31 and force it inwardly against the tension of spring 31^h. 25 This action causes the hook 31^c to be thrown outwardly.

The cam 28^a is engaged on its under side by a pin at the inner end of an arm 33, which is pivotally mounted upon a boss 33^a 30 extending downwardly from the plate 26. The other arm of this lever extends to the left and is designated as 33^b. Its outer end is slotted to receive and actuate the pin 34 carried by an arm 34^a of a bracket which 35 is pivoted at the lower end of a boss 34^b extending downwardly from the plate 26. This pivoted bracket has a rearwardly extending arm 34^c, which pivotally supports 40 at its rear end a lever having a rearwardly extending arm 35 and a forwardly extending arm 35^a. The arm 35^a has a downwardly extending pin 35^b at its rear end and the arm 35^a has a slot 35^c at its front end. The pin 35^b is engaged by the arm 30^c to turn 45 the lever 35, 35^a at the proper moment. There is also a fixed pin 36 carried on the top of the plate 36^a, which plate extends to the left from a support 36^b extending downwardly from the plate 26. This pin 36 is 50 engaged at a suitable time by the arm 35^a to turn the same about its pivot.

The above described pivoted bracket having arms 34^a and 34^c also carries an arm 34^d, which extends to the left and in its outer 55 end has pivoted a little crank, the rear end 37 of which extends diagonally upward and through the slot 35^c. The other part of this crank has an upward extension 37^a and at right angles thereto a forward extension 60 37^b, at the end of which is a pin 37^c.

It should be noted that although the cams 28^a, 28^b and 28^e are engaged upon their under side by the levers controlled thereby and the cam 28 on its upper side, yet for

simplicity the development of the cams 65 shown in Fig. 7 is shown relatively as if they were all engaged on the same side, so that the sequence of movement can be more clearly followed from Fig. 7, beginning at the top of Fig. 7 and passing to the lower 70 part. In reality, in the particular construction described, the development of cam 28 should in Fig. 7 be shifted 180° in relation to the other three cams.

The operation of the device as a whole 75 will now be described. The gear 5 being driven from a suitable source causes the upper mechanism and bridge to be raised to the position shown in Figs. 1 and 2 by the cams 12, and remain raised by these cams 80 during the initial operation of the lower mechanism. The attendant inserts the package A on the base plate under the plate 1^a. The ribbon or cord 15 having been previously cut by the cutting mechanism has 85 left an end of the ribbon at the right of the machine. The ribbon drawer 18, 18^b has been moved to the right and the arms 24, 25 have been moved toward each other to the positions shown in Figs. 1, 2 and 3, so that 90 the arms 22 and 23 are criss-crossed over each other with the fingers at their ends open to receive the ribbon. In the right-hand position of arm 18^b, the fingers 21^a, 21^b have been caused to open about the new 95 end of the ribbon as shown in Fig. 8 and as already described. Referring to the cams of Fig. 4, and starting at the top, it is evident that the cam 9^a will first cause the pin 17^b of the lever 17 to move to the left and 100 consequently cause the arm 18^b to be thrown from the right to the left to assume the position shown in Fig. 3. In moving from the right, the fingers at its end first close about the ribbon and then draw it along to 105 the left on a path determined by the contour of the inner edge of plate 20, as already described. In making this movement, it will be seen that the ribbon is threaded between the fingers 22^a and 22^b of the arm 22 110 and then in moving farther along the edge of plate 20, the post 21 of the arm 18^b and the ribbon is carried inwardly so as to pass back of the fingers 23^a and 23^b. In the latter part of the movement of the arm 18^b and 115 post 21, the contour of plate 20 causes the same to move toward the front of the machine to the position shown in Fig. 3 and thereby threads the ribbon in between the fingers 23^a, 23^b, all of the parts then having 120 the position shown in Fig. 3.

The cam 13 on pivot 11 is so placed that it now permits the cutting plunger to be thrown upwardly to cut the ribbon as already described, the cutting plunger then 125 being forced down where it remains until it is again called upon to cut the ribbon for the next package.

Referring again to Fig. 4, it will be seen that after the cam 18^a has been thrown to the left, the levers 24 and 25 are next moved away from each other by the action of the cams causing the pedestals 22^b and 23^b to be moved along the inclined slots as already explained. In this movement the distant ends of the arms 22 and 23 are also raised and carry the ends of the ribbon upwardly over the package and over the plate 1^a, the end of arm 22 being raised a little higher than the end of the arm 23 by the construction already described so as to permit the ends to pass each other. This movement ties the first knot by reason of the initial criss-crossed or double crossed position of the arms 22, 23. Thus it will be seen that when the fingers 22^c and 22^d raise the right-hand portion of the ribbon and passes it to the left, it carries it over the arm 23 as the latter moves to the right; and the fingers 23^c and 23^d will at the same time carry the left-hand portion of the ribbon over the arm 22 as the latter moves to the left, bringing the parts and the ribbon to the position shown in Fig. 5 with the parts 15^a and 15^b of the ribbon extending from the knot upward diagonally and in an inclined direction.

After the above step, it will be seen by Fig. 4 that the cams of the lower mechanism permit the parts to remain at rest for a considerable period during which the upper mechanism completes the tying of the bow.

Thus as soon as the parts have assumed the position of Fig. 5, the cams 12 permit the upper mechanism and bridge to drop and the pin 29^b then impinges upon the center of the first knot of the ribbon and holds it against the plate 1^a during the operation of the upper mechanism.

The bridge now having been lowered and the pinion 27^a engaged by the gear 5, it will cause the cam shaft 27 to be turned one revolution and cause a sequence of movements of the parts as determined by the cams 28 to 28^c. Referring to Fig. 7 and starting at the top of the figure, it will be seen that the first action is caused by cam 28^b which turns the arm 31 from the right to the left about its pivot to the position shown in Fig. 6; and the position of the parts shown in Fig. 6 is that which they occupy at the time the arm 31 has first been thrown to the left. Before the arm 31 was moved somewhat to the left from its initial position, the arm 31^b was positioned inward sufficiently so that when the bridge was lowered, the arm 31^b and parts carried thereby would clear the portion 15^b of the ribbon. After the bridge is down, the cam 28^b then causes, in the action just described, the arm 31^b to be moved somewhat under the ribbon and the hook 31^c to be located in the rear of and a little be-

yond the shaft 29^a in the position shown in Fig. 6.

Cam 28^a next acts to throw the arm 33 from the position shown in Fig. 6, to the right. This causes the slotted end of arm 33^b to move toward the rear of the machine and thereby carries the pin 34 and the above described bracket in a counter-clockwise direction about their pivot. In this movement the finger 37^c engages the portion 15^c of the ribbon on its under side and forms a loop therein over the end 37^a which is carried toward the shaft 29^a in a raised position. In this movement the left-hand end of the ribbon is consequently drawn by force out of the fingers 22^c and 22^d, causing this portion of the ribbon to hang in a vertical loop over the pin 37^a near the shaft 29^a and to the rear of the same in the position shown in Fig. 10. These parts then momentarily remain in this position as shown by the contour of the cam 28^a.

The cam 28 next acts to control the hook 29ⁱ. Thus it will be seen from Fig. 7 that the arm 30 is first thrown to the right a certain distance and that amount of movement is sufficient to draw the rack 29 to the left, causing the pinion 29^c to be rotated counter-clockwise about half a revolution. When the hook 29ⁱ starts to move, it swings under the upwardly extending part 15^b of the ribbon, catching the same in a loop and drawing it by friction out from between the fingers 23^c and 23^d of the arm 23. By reason of the cam shaped surfaces of the abutting sleeves 29^d and 29^f and by reason of the shape of the disk 29ⁱ, the hook 29ⁱ carries its loop of the ribbon in a curved path rearwardly and downwardly around the back of the vertically upward extending loop 15^a, which latter is being held in such vertical position near the shaft by the pin 37^c. In carrying the loop of the portion 15^b of the ribbon down and around the vertically extending loop, the hook 29ⁱ carries its loop of the ribbon to and on to the hook 31^c, which has already been placed in position to receive it by the action already described.

The parts then have the position shown in Fig. 10 and it will be noted that the arm 31^d when located inwardly under the portion 15^b of the ribbon, is near the vertical shaft 29^a and beyond it; and when the pin 37^c swung its loop of the ribbon to the rear of the shaft 29^a, it caused its loop to be passed beyond and with its loose end extending under the arm 31^d and hook 31^c so as to assume the position shown in Fig. 10. When the hook 29ⁱ has carried its loop around the other loop, as already stated, the hook 29ⁱ then passes its loop of the ribbon on to the finger or hook 31^c as indicated in Fig. 10.

Again referring to Fig. 7, the next operation is caused by the cam 28^b moving the

arm 31 to the left and thus causes the hook 31^e, which now has one loop of the ribbon, to be drawn toward the front of the machine to assume the position in which it is shown in Fig. 11. Thus one loop of the ribbon is drawn out in a diagonal direction to form part of the bow as shown in Fig. 11. While this latter movement is taking place, the cam 28 first causes the arm 30 to be moved 10 a further amount to the right by the action of the right-hand portion of the groove in cam 28; and this further movement causes the arm 30^f to be moved from the position shown in Fig. 10 to the position shown in 15 Fig. 11. In this movement the arm 30^f strikes against the rear of pin 35^b, which rotates the arms 35 and 35^e about their pivot on the end of arm 34^e and thus causes the slot in the end of arm 35^a to turn the arm 50 37 of the bell crank lever from the position shown in Fig. 10 over to the position shown in Fig. 11. This movement causes the finger 37^e which has been holding one loop of the ribbon vertically upward to be turned then 55 to the rear laying out its loop of the bow in the horizontal position shown in Fig. 11. These actions complete the forming of the bow.

During the further revolution of the cam 30 shaft 27, and while the arm 31^d and hook 31^e are normally in the position shown in Fig. 11, the cam 28^e causes a movement of the arm 32 to the right about its pivot and so causes the arm 32^b to be moved to the left 35 and strike against the projection 31ⁱ of the arm 31^e. This forces the arm 31^e to the left about its pivot against the tension of spring 31^h and thereby throws the hook 31^e out from its loop of the ribbon, the spring 31^h 40 afterward causing it to be returned to its normal position with relation to the arm 31^b.

It will be seen from further considering Fig. 7 that the parts are returned to their starting positions. Thus the cam 28 causes 45 the lever 30, 30^e to be returned to the position shown in Fig. 6, the rack bar 29 operating the gear 29^c to cause the hook 29ⁱ to be turned and raised to its initial position. Likewise the cam 28^e causes its lever to be 50 returned to the position shown in Fig. 6; and the cam 28^b causes its lever to be moved from the position shown in Fig. 11 to place the hook 31^e inwardly at its extreme inner position. Likewise the cam 28^a causes the 55 lever arm 33 to be moved to the left from the position shown in Figs. 10 and 11 to that shown in Fig. 6. This causes the slotted end of the arm 33^b to be moved forwardly from the position shown in Figs. 10 and 11 and so cause the aforementioned bracket to be turned clockwise about its pivot, which causes the pin 37^e to be withdrawn from its loop of the ribbon and the bracket then placed again assumes the po-

sition shown in Fig. 6. As it comes to this 65 position, the arm 35^a strikes against the fixed pin 36. This causes the lever 35, 35^a to be turned clockwise about its pivot and turn the arm 37 of the crank so as to raise the pin 37^e to its upright position. 70

The cam shaft 27 has now made a complete revolution, at the completion of which the cams 12 on the shaft 11 raise the upper mechanism from the base portion of the machine to again assume the position shown 75 in Figs. 1 and 2. The attendant does of course remove the package A from the machine as soon as the tying of the bow is completed and immediately inserts another package, so that by the time the arms 22 and 23 start 80 to operate again to wrap the package, the package has already been placed in position over the new length of ribbon which has been drawn under the package and cut off as already described. It is evident that the 85 above described cycle of operations is again passed through by continued operation of the machine giving the quick, efficient and neat tying of a ribbon in a bow around packages in succession. 90

It will be evident to those skilled in the art that various adjustments and modifications of the parts and their particular shape may be readily made in the machine in adapting it to operate upon various types 95 and sizes of packages and with various forms and widths of ribbons or cords.

It will be seen from the foregoing description that the method of operation and wrapping and tying the bow is reduced to the 100 simplest character of steps and in the above described preferred form of my invention, the ribbon or cord is drawn by two bars double crossed with relation to each other, over the package so as to produce the first knot 105 by the simple step of drawing the ends of the ribbon over the package. The ends of the ribbon are then held out in proper position to be manipulated while the first knot of the bow is held in the fixed position. One loop of the ribbon is then caused to be held vertically near the first knot and the other loop drawn around it and between it and the knot and under a portion of the ribbon extending from the knot so that when 115 the two loops are drawn, the bow is tied and the loops and the ends of the ribbon then placed in the proper relation to each other.

When the machine is used for wrapping 120 and tying bow knots upon packages of envelopes, the envelopes are somewhat compressed by the attendant in setting them under the plate 1^a. When the bow is tied about the envelopes, the same length of ribbon and of its parts is uniformly made by the attendant, the package expanding 125 slightly so as to place a certain amount

of tension on the ribbon. Thus when envelopes are made up in packages say of twelve for the machine, each package after wrapping will have the same thickness, even though the stock from which envelopes are made is different. Thus the envelop packages are always made up of proper and uniform thickness to exactly occupy the space provided for them in the boxes in which they are afterward packed.

Although I have described a preferred method and machine embodying my invention, it will be understood that various modifications may be made therein without departing from the scope thereof; my invention is also applicable to various uses and may be applied to wrapping and tying articles of various shapes, sizes and types.

Where I have used the term ribbon in the claims, it will be understood that the term is there used in a sense broad enough to include not only a flat ribbon but a cord of ribbon of any shape suitable for wrapping and tying articles or packages.

25 I claim:

1. A machine for tying packages with a ribbon comprising double crossed arms for drawing the ribbon over the package, and means for moving said arms to form a knot in the ribbon.

2. A machine for tying packages with a ribbon comprising a pair of devices movable away from each other for drawing a ribbon over the package and for looping the same in a knot, and means for moving said devices.

3. In a machine for tying packages with a ribbon, an arm extending over the package for grasping the ribbon on the opposite side, a second arm extending over the package in the opposite direction for grasping the ribbon on the other side thereof, said arms passing over and under each other, and means for moving said arms to draw the ribbon around the package and form a knot.

4. In a machine for tying packages with a ribbon, a base, an arm adapted to extend over the package and receive one end portion of the ribbon, a second arm adapted to extend over the package and receive the other end portion of the ribbon, said arms crossing over and under each other, and means for causing said arms to be moved along said base to draw the ribbon over the package and form a knot.

5. In a machine for tying packages with a ribbon, an arm extending over the package to receive an end portion of the ribbon at one side of the package, a second arm extending over the package to receive an end portion of the ribbon at the other side of the package, said arms passing over and under each other, and means for drawing said arms apart and for also raising said arms to

wrap the ribbon around the package and 65 form a knot.

6. In a bow tying machine, means for forming one loop of the bow, and means for forming another loop of the bow and carrying it around the first loop.

7. In a bow tying machine, means for forming and holding one loop of the bow in an upright direction from the knot, and means for forming another loop of the bow and carrying it around said first loop.

8. In a bow tying machine, means for forming and holding one loop of the bow in an upright direction from the knot, and means for forming another loop of the bow and carrying it around said first loop and 80 for drawing the second loop through a turn of the ribbon.

9. In a bow tying machine, means for holding the first knot in a fixed position, and means for forming and tying the bow while 85 the first knot is so held.

10. In a bow tying machine, means for holding the first knot in position, means for forming and holding one loop of the bow in an upright position from said knot, and 90 means for forming another loop of the bow and passing it around the first loop and between the loop and said holding means and for drawing the second loop to form the bow.

11. In a bow tying machine, an upright device for holding the first knot in a fixed position, means for forming and holding one loop in an upright position, means for forming another loop and passing the same 100 around the first loop and between the first loop and said device and for drawing the second loop to form the bow.

12. In a bow tying machine, a device for tying the first knot and holding the end portions in certain positions, means for engaging one end portion to form one loop, means for engaging the other end portion to form a second loop and for passing same around the first loop and forming the bow.

13. In a bow tying machine, a device for forming the first knot, an element for holding said knot in a fixed position, and means for forming two loops of the bow and passing one of said loops around the other.

14. In a wrapping and tying machine, means for drawing a ribbon under the package, means for cutting off a length of ribbon, means for drawing the end portions of the ribbon around the package and forming a 120 first knot, and means for engaging the end portions of the ribbon and for forming loops therein and tying the bow.

15. In a wrapping and tying machine, means for drawing a ribbon under the package, means for cutting off a length of ribbon, means for drawing the end portions of the ribbon around the package and forming a

first knot, means for engaging the end portions of the ribbon and for forming loops therein and tying the bow, and means for driving the mechanism of the machine from 5 a single source.

16. In a wrapping and tying machine, means for drawing a length of the ribbon and for cutting off said length, means for wrapping the ribbon around the package 10 and forming the first knot, an element for holding said knot in a fixed position, means for forming one loop of a bow, means for forming another loop and passing the same around the first loop and between the first 15 loop and said element and for drawing the second loop to form the bow.

17. In a wrapping and tying machine, means for carrying a ribbon around the package and forming a knot with the end 20 portions extending diagonally from said knot, a device for engaging one end portion for forming a loop, another device for engaging the other end portion for forming a second loop, and means for causing the loops 25 to be positioned to form a bow.

18. In a wrapping and tying machine, a lower mechanism for wrapping a ribbon around the package and forming the first knot, and an upper mechanism movable as 30 a whole for forming the bow.

19. In a wrapping and tying machine, a lower mechanism for drawing a length of ribbon, for cutting off a length of ribbon and for wrapping same around the package 35 to form a first knot, and an upper mechanism movable as a whole toward and away from the lower mechanism for forming the bow.

20. In a wrapping and tying machine, 40 a lower mechanism for wrapping the package and forming the first knot, another mechanism movable to and from said lower mechanism for forming a bow, said upper mechanism being driven and operated by the 45 lower mechanism.

21. In a wrapping and tying machine, a lower mechanism for wrapping a ribbon around the package and forming the first knot, and for holding the end portions of 50 the ribbon in inclined positions extending

from said knot, and a mechanism movable to and from the wrapped package for holding said knot in a fixed position, for engaging one of said end portions to form a loop and for engaging the other end portion to form 55 a loop and for forming a bow.

22. In a wrapping and tying machine, a device for drawing a ribbon, a device for cutting off a length of ribbon, means comprising a pair of movable elements for drawing the ribbon around the package and forming a knot, and a plurality of cams for controlling the operation of the parts. 60

23. In a wrapping and tying machine, a mechanism for wrapping a ribbon around 65 the package and forming the first knot, another mechanism movable to and from the first mechanism for forming a bow, and a plurality of inter-related cams for controlling the sequence of operations of said mechanisms. 70

24. The method of wrapping and tying a package consisting in positioning a ribbon under the package, grasping the end portions thereof in a double crossed relationship and drawing said end portions toward and past each other around the package. 75

25. The method of wrapping and tying a package consisting in positioning a ribbon under the package, grasping the end portions thereof in a double crossed relationship and drawing said end portions toward and past each other around the package to form the first knot, holding said knot in fixed position, forming a loop in one end portion, 80 forming a loop in the other end portion, and positioning said loops to form a bow. 85

26. The method of wrapping and tying a package consisting in positioning a ribbon under the package, drawing the end portions of the ribbon around the package and forming the first knot, holding said knot in a fixed position, forming a loop in one end portion and extending in an upright position from said knot, forming a loop in the 90 other end portion and passing the same around the first loop and drawing the second loop to form a bow. 95

HENRIK J. SCHMIDT.
